(57) **CLAIM**

The ornamental design for a support structure of a chair, as shown and described.

DESCRIPTION

FIG. 1 is a left side elevational view of a support structure of a chair showing my new design;

FIG. 2 is a right side elevational view showing the design of the support structure of FIG. 1;

FIG. 3 is a back elevational view showing the design of the support structure of FIG. 1;

FIG. 4 is a front elevational view showing the design of the support structure of FIG. 1;

FIG. 5 is a top elevational view showing the design of the support structure of FIG. 1; and,

FIG. 6 is a perspective view showing the design of the support structure of FIG. 1.

In FIGS. 1–6, the broken lines showing the seat member, the feet members, and the back support member are for illustrative purposes only and form no part of the claimed design.
